UNITED STATES PATENT OFFICE.

WILLIAM McSHANE, OF ST. JOHN, NEW BRUNSWICK, CANADA, ASSIGNOR
TO THOMAS McAVITY, JOHN McAVITY, AND GEORGE McAVITY, OF
SAME PLACE.

INJECTOR.

SPECIFICATION forming part of Letters Patent No. 431,613, dated July 8, 1890.

Application filed March 26, 1890. Serial No. 345,343. (Model.)

To all whom it may concern:

Be it known that I, WILLIAM McSHANE, a subject of the Queen of Great Britain, residing in St. John, county of St. John, Province 5 of New Brunswick, and Dominion of Canada, have invented certain new and useful Improvements in Injectors, of which the following is a specification.

My invention relates generally to injectors, 10 and particularly to that class thereof known as "double-tube injectors," one tube of which is designed to draw water from the source of supply and deliver it to the second tube, which forces it into the boiler.

15 The object of my invention is to provide an injector of the class described which shall be simpler and more compact in its construction and more efficient and convenient in its operation.

20 With this object in view my invention consists in providing a double-tube injector having overflow and discharge passages with an additional passage communicating with the force-tube and overflow-passage, and the 25 tubular two-way cock establishing said communication.

My invention consists, further, in certain details of construction and combination of parts, such as shown in the drawings and set forth 30 in the description.

In the accompanying drawings, Figure 1 is a vertical longitudinal section of my improved injector. Fig. 2 is a transverse vertical section taken on the plane of the line 2 2 of Fig. 35 1; and Fig. 3 is a detail view of the washer, lug, and connecting-rod.

35 In the embodiment of my invention I employ a casing A, containing lifting and forcing appliances, said casing being connected 40 with the steam and water supplies by means of the pipes S and W, respectively. The overflow passage D and the discharge-passage E are preferably formed integral with the casing of the injector.

45 The lifting apparatus consists, as usual, of the steam-chamber S'', lifter steam-nozzle a, and the lifter combining-tube b, and the forcing apparatus consists of the force steam-nozzle c, force combining-tube d, and the

steam-chamber communicates also with this 50 apparatus. The lifting and forcing devices are connected by means of the horizontal chamber J and the vertical chamber C''. All of the said parts for lifting and forcing the water may be of any approved pattern; but 55 it is preferred to employ constructions at least somewhat similar to those shown in my patent, No. 362,300, dated May 3, 1887.

Directly beneath the force combining-tube is formed the passage C, which curves off in 60 its downward course and joins the discharge-passage E. At the juncture of the chambers J and C'' is formed an additional passage B, said passage extending downward and communicating with the passages C, D, and E by 65 means of the two-way tubular cock or plug F, arranged in the casing at the juncture of the passages B and C and the overflow-passage D. The passage B is preferably larger at its upper extremity.

70 The operating-lever F' is secured upon one end of the plug F, said lever being provided with a lug F'', which engages a stop F''', formed upon the casing, to limit the movement of the lever. A washer H is arranged 75 upon the opposite end of the plug, said washer having the eccentric lug H', slotted as shown at H''' in Fig. 3. The connecting-rod G is secured at its lower end to the eccentric lug by means of the screw or bolt H'', working in 80 the slot of the said lug. The upper end of the connecting-rod is rigidly connected with the valve-spindle K, which operates the valve L, to close and open the same in concert with the opening and closing of the plug F. 85

The construction of my improved injector having been fully described, I will now describe its operation.

We will suppose the steam and water passages to be open. In this class of injectors it 90 is necessary to have a communication between the lifter side of the injector and the external atmosphere. This communication is had directly with the air by means of the passage B and the two-way cock F, the plug being so 95 turned that communication is established between the passages B, C, and D. The valve L is now closed. The water is drawn through

the pipe W and forced into the chamber J, where it immediately flows into the passage B through the two-way cock F and out through the overflow-passage D. The lever F' is now 5 shifted until the lug F'' comes in contact with the stop F''', which limits its movements and renders its action positive and certain. The cock in being so turned operates the connecting-rod G and opens the valve L, when the 10 forcer side of the injector is set into operation.

I am aware that passages have been made communicating with the forcer side of the injector and the overflow, and that valves have been employed to regulate said passage; but 15 in all of these devices, so far as I am aware, there is a very complicated arrangement of valves, rendering the device expensive, difficult in its operation, and greatly impairing its efficiency, whereas in my improved injector 20 the two-way cock is much simpler, cheaper, and more efficient than a complicated set of levers. The lever being provided with the stop limits the motion of the same, and the slotted lug on the washer, to which the connecting-rod is attached, insures a positive 25 vertical movement of said rod.

Having thus described my invention, its operation, and advantages, what I claim as new 30 is—

1. An improved injector consisting of a double tube-casing A, having the overflow D,

discharge E, and passage B, communicating with the forcer side and the overflow, the two-way cock F, communicating with the passage B, overflow D, and discharge E, lever F', for 35 operating said cock, washer H, connecting-rod G, and valve-spindle K, operating the valve L, all arranged so that when the cock F is open the valve is closed, and vice versa, substantially as shown and described. 40

2. An improved injector consisting of the double-tube casing A, having the overflow D, discharge E, and passage B, leading from the forcer side of the injector to the overflow, the two-way cock F, establishing communication 45 between the passage B, overflow D, and discharge E, the lever F', for operating the said cock, said lever having the lug F'', adapted to contact with the stop F''', the washer H upon one end of the cock, the eccentric lug H', 50 formed upon the washer and slotted at H''', the connecting-rod G, and means for connecting the same to the eccentric lug, the steam-valve L, and spindle K, all arranged so that when the valve L is opened the cock F is 55 closed, and vice versa, substantially as and for the purpose set forth. 50

WILLIAM McSHANE.
